UNITED STATES PATENT OFFICE.

FRANK DEGNER, OF SALEM, SOUTH DAKOTA.

HAT-PIN GUARD.

1,085,327.

Specification of Letters Patent.

Patented Jan. 27, 1914.

Application filed June 27, 1913. Serial No. 776,015.

To all whom it may concern:

Be it known that I, FRANK DEGNER, a citizen of the United States, residing at Salem, in the county of McCook and State 5 of South Dakota, have invented certain new and useful Improvements in Hat-Pin Guards; and I do hereby declare the following to be a full, clear, and exact description of the invention, such as will enable 10 others skilled in the art to which it appertains to make and use the same.

This invention is in the nature of a hat pin guard for protecting the exposed sharp point of a hat pin, and the primary object 15 of the invention is to provide a device of this character which, while neat and economical in construction, will be capable of fulfilling all the requirements of such devices in use.

A further object of the invention is to 20 provide such a simple and economical structure which may be readily placed upon and removed from the exposed point of the pin, and at the same time be held tight enough to prevent accidental removal and loss while 25 in use.

With these objects in view, the invention consists in the improved construction, arrangement and combination of the parts of 30 a device of the character specified, which will be hereinafter fully described, and afterward specifically claimed.

In order that the construction and operation thereof may be readily comprehended, I will now proceed to fully describe my invention in connection with the accompanying 35 drawings, which illustrate an approved embodiment thereof, and in which drawings—

Figure 1 represents the guard in side elevation with a pin inserted therein. Fig. 2 represents a vertical central longitudinal view through the guard with the point of the pin inserted therein, part of the pin being broken away. Fig. 3 represents a transverse 40 sectional view taken on the plane indicated by the broken line 3—3 of Fig. 2. Fig. 4 represents a similar sectional view of a slightly modified form, the section being taken on a plane corresponding to that indicated by the broken line 4—4 of Fig. 2.

Like reference characters mark the same parts wherever they occur in a plurality of the figures of the drawing.

Referring specifically to the drawing, 55 indicates the body of the structure which is tubular and may be made of any suitable

material such as wood, bone, ivory, metal or the like, and may be suitably ornamented on its outer surface, as may be desired.

In order to properly hold the pin in the 60 central opening of the body 5, it is necessary to provide a suitable packing, having the required qualities to cause it to grip the pin when inserted tight enough to prevent its accidental removal, and at the same time to 65 permit of its ready removal therefrom when desired, and for this purpose I propose to dispense with all springs or other metallic substances within the body of the guard, such having been found objectionable in 70 use. Therefore, in carrying out my invention I provide a filling of some material such as flax, hemp, etc., which will perform all the functions of those heretofore used, and at the same time avoid their objection- 75 able points. As best shown in Fig. 2, 6 indicates threads of hemp, flax or like material which are passed longitudinally through the body tube of the guard, tied into a large knot or bunch at 7 at the outer 80 end of said body for the purpose of preventing them being pulled through the guard upon the withdrawal of the pin, and at their opposite ends are turned outward as at 8, over the edges of the body, where 85 they are tightly held by a sleeve 9, which is preferably made of suitable ornamental metal but may be made of any other suitable material, the body of the guard being slightly reduced from the end to the point 90 10 to accommodate the sleeve 9 and bring its outer surface into smooth alinement with the outer surface of the body.

A suitable cap 11 is passed over the outer 95 end of the body, inclosing the knot or bunch 7 of material before referred to, the body being likewise reduced at this end to accommodate the cap in the same manner as referred to in reference to the sleeve 9, so as to leave a smooth uninterrupted surface 100 throughout the length of the guard. The cap 11 may be made of any suitable ornamental material, metal probably being preferred. There may be as many of these threads as can be readily accommodated in 105 the bore of the body of the guard and in the construction of Figs. 2 and 3, I have shown four, although I do not wish it to be understood that I restrict myself to any particular number.

When the point of the pin is inserted into the guard, it compresses these threads out-

ward and they grip the pin with sufficient firmness to prevent its accidental displacement, and at the same time permit of its ready removal. Should the pin be inserted 5 the full length of the body, its point will embed itself in the knot or bunch of the filling material, at 7, which will prevent its further advancement and its contact with the cap 11, to the injury of the cap and pin 10 point.

Owing to the peculiar flexible qualities of the material which I use for a filling, it will resume its normal condition and position when the pin is removed, ready for repeated 15 insertions, the flexibility of the hemp, flax or like material adapting it to the use to which I have put it and providing a much improved filling material for such hat pin guard.

20 While I have shown, especially in Fig. 2, the body made of some other material than metal, I have illustrated the same, made of thin metal, in Fig. 4 of the drawing, in which 9^a indicates the sleeve corresponding 25 to the sleeve 9, 6^b the turned over ends of the filling material, and 6^a the body of the guard made of thin sheet metal. The turned over ends of the filling material at 30 6^b are firmly clamped between the body 6^a and the sleeve 9^a while the interior of the metallic body 6^a is filled with the threads 6^c of the filling material, the thinness of the material of the body affording room for a 35 greater number of threads of the filling material.

It will also be obvious that with the body 40 made of thin metal, the guard may be made thinner than when constructed of such material as wood, bone or ivory, and at the same time will accommodate as many threads of the filling material.

While I have specifically described the

exact construction and arrangement of the component parts of my invention, it will be 45 obvious to those skilled in the art to which the invention most nearly appertains, that slight changes and variations may be made therein, within reasonable limitations, without departing from the spirit and scope of the invention.

Having thus fully described my invention, what I claim and desire to secure by Letters Patent of the United States is:—

1. A hat pin guard comprising a tubular body, a filling material of hemp, flax or like 55 flexible material, means at the outer end of the guard to prevent the material from being pulled therethrough, the ends of the material being turned outward over the end of the body, and securing means at the 60 inner end of the guard comprising a sleeve passed over said turned over ends and the end of the body.

2. A hat pin guard comprising a tubular body, threads of hemp, flax or like flexible 65 material passed through the body and gathered at its outer end, its opposite ends being turned outward upon the end of the body, a cap passed over one end of the body to protect the gathering of material, and a 70 sleeve passed over the opposite end to inclose and hold the turned over ends of the filling material, the gathering of filling material serving also as a cushion for the point of the pin when inserted the full length of 75 the body.

In testimony whereof I have signed my name to this specification in the presence of two subscribing witnesses.

FRANK DEGNER.
